(57) **CLAIM**

The ornamental design for a stock butt pad, as shown and described.

DESCRIPTION

FIG. 1 is a right side elevation view of a stock butt pad attached to a firearm showing our new design;

FIG. 2 is a right, top, rear perspective view of the stock butt pad of FIG. 1;

FIG. 3 is a rear elevation view of the stock butt pad of FIG. 1;

FIG. 4 is a right side elevation view of the stock butt pad of FIG. 1;

FIG. 5 is a front elevation view of the stock butt pad of FIG. 1;

FIG. 6 is a left side elevation view of the stock butt pad of FIG. 1;

FIG. 7 is a top plan view of the stock butt pad of FIG. 1; and, FIG. 8 is a bottom plan view of the stock butt pad of FIG. 1. The broken lines showing portions of the design in all figures are included for the purpose of illustrating environment and unclaimed features and forms not part of the claimed design.

1 Claim, 3 Drawing Sheets
